UNITED STATES PATENT OFFICE.

CLARENCE L. HENDERSON, OF BRASHEAR, MISSOURI.

FLUE-THIMBLE.

No. 890,140.

Specification of Letters Patent.

Patented June 9, 1908.

Application filed June 12, 1907. Serial No. 378,623.

To all whom it may concern:

Be it known that I, CLARENCE L. HENDERSON, citizen of the United States, residing at Brashear, in the county of Adair and State of Missouri, have invented certain new and useful Improvements in Flue-Thimbles, of which the following is a specification.

The present invention relates in general to stove pipes and more particularly to a novel clamping device for securely retaining a stove pipe in engagement with a flue thimble.

The object of the invention is to provide a simple and inexpensive device of this character which operates in an effective manner to prevent the end of the stove pipe from slipping away from the thimble, and eliminates the necessity for wiring the pipe as is frequently the custom.

For a full description of the invention and the merits thereof and also to acquire a knowledge of the details of construction and the means for effecting the result, reference is to be had to the following description and accompanying drawings, in which:

Figure 1 is a side elevation showing the clamping device applied to a stove pipe thimble, portions being broken away. Fig. 2 is a transverse sectional view. Fig. 3 is a detail view of the clamping ring and retaining strips.

Corresponding and like parts are referred to in the following description and indicated in all the views of the drawings by the same reference characters.

Referring to the drawings the numeral 1 designates a flue thimble which is of the conventional construction, and 2 a stove pipe having the end thereof received within the thimble. A clamping ring 3 surrounds the stove pipe 2 adjacent the mouth of the thimble and is held in position by means of the retaining strips 4.

In the embodiment of the invention shown in the first three figures of the drawings the clamping ring 3 is in the nature of a band having the extremities thereof extended outwardly and connected by the bolt 5. The retaining strips 4 engage the clamping ring 3 and extend longitudinally along the exterior of the thimble 1 upon opposite sides

thereof, and are connected to the said thimble by means of the rivets or similar fastening members 6.

The rear end portions of the retaining strips are extended laterally to form projections 7 which serve to engage the partition or wall through which the flue extends, thereby effectively preventing the pipe 2 slipping away from the flue or the flue thimble being withdrawn from position.

In the preferred form of the invention the retaining members 4 are in the nature of sheet metal strips doubled upon themselves at their intermediate points whereby the loops 8 are formed for the reception of the clamping ring 3. It will be observed that the said retaining strips 4 are provided adjacent their outer ends with crimp portions constituting the stops 12 and operating to engage the wall or partition through which the thimble extends to hold the same securely in position.

In applying the flue thimble it will be obvious that the same may be either built into the wall or the extremities of the retaining strips bent to form the projections 7 subsequent to placing the thimble in position within the opening in the wall.

Having thus described the invention, what is claimed as new is:

1. In a device of the character described, the combination of a flue thimble, a clamping ring arranged adjacent the mouth of the flue thimble, and retaining strips projecting beyond the flue thimble and engaging the clamping ring, the said retaining strips extending longitudinally along the flue thimble and being rigidly secured to the same, the rear ends of the strips being provided with lateral projections to engage the rear face of the wall while intermediate portions of the retaining strips are formed with stops for engaging the front of the wall.

2. In a device of the character described, the combination of a flue thimble, a clamping ring arranged adjacent the mouth of the thimble, and retaining strips formed by doubling a strip of sheet material upon itself and extending beyond the flue thimble to form loops for receiving the clamping ring, the said retaining strips extending longitudinally along the exterior of the thimble upon opposite sides.

dinally along the flue thimble and being secured thereto, the rear end of each of the strips being provided with a lateral projection to engage the rear face of the wall, while
5 an intermediate portion of each of the strips is crimped for engagement with the front face of the wall.

In testimony whereof I affix my signature in presence of two witnesses.

CLARENCE L. HENDERSON. [L. S.]
